UNITED STATES PATENT OFFICE.

CHARLES E. RUSSELL, OF CAMBRIDGE, MASSACHUSETTS, ASSIGNOR TO STONE TELEGRAPH
AND TELEPHONE COMPANY, OF BOSTON, MASSACHUSETTS.

OSCILLATION-DETECTOR.

No. 899,264.

Specification of Letters Patent.

Patented Sept. 22, 1908.

Application filed September 4, 1906. Serial No. 333,041.

To all whom it may concern:

Be it known that I, CHARLES E. RUSSELL, a citizen of the United States, and a resident of Cambridge, in the county of Middlesex and 5 State of Massachusetts, have invented a new and useful Improvement in Oscillation-Detectors, of which the following is a specification.

My invention relates to wireless telegraph 10 receiving devices or oscillation detectors, and the object of my invention is to produce a simple and very sensitive oscillation detector of the general type known in this art as "magnetic detectors", which shall not require a cyclically varying magnetic field.

My invention will be described with reference to the drawings which accompany and form a part of this specification and which illustrate one form of magnetic detector embodying the principles of my invention, although it is to be understood that I do not limit myself to the particular embodiment thereof which is illustrated in said drawings, inasmuch as many modifications may be 25 made therein without departing from said principles.

In the drawings Figure 1 is a diagram illustrating my invention in its simplest form. Fig. 2 is a front elevation partly in 30 section of a practical embodiment of my invention. Fig. 3 is a section taken on the line 3—3 of Fig. 2. Fig. 4 is a diagram showing a set of curves drawn to rectangular co-ordinates in which the ordinates represent 35 magnetic induction and the abscissæ represent magnetomotive force.

In the drawings, V represents an elevated conductor including the primary I_1 of a transformer, the secondary of which I_2 , is serially 40 included in a resonant receiving circuit which contains the condenser C, the coil L and the solenoids 2, 2 which may consist of a few turns of stranded wire.

1 represents a permanent magnet which 45 forms a practically closed magnetic circuit and to which the soft iron cores 2' are magnetically connected.

3 represents a movable magnetizable member forming part of the magnetic circuit comprised by the permanent magnet 1, and which may be a diaphragm similar to those employed in magneto telephones. A carbon button 6 may be secured to the center of 55 said diaphragm so as to form a variable contact with the pin 4 which is electrically con-

nected with the magnet 1 and which may be adjusted by means of the milled head 5. Although not absolutely essential to operativeness, I prefer to employ an adjustable permanent magnet 7 arranged as shown for the purpose of balancing the normal pull exerted on the diaphragm 3 by the magnetic flux existing in the magnets 1, 2'.

R is a resistance and B is a battery, the resistance and battery constituting a potentiometer for adjusting the electromotive force impressed on the circuit including the telephone T, the diaphragm 3, the carbon button 6 and the pin 4.

The operation of my invention may be understood by having reference to Fig. 4. In Fig. 4 curve (1) represents the variation with cyclically varying magnetomotive force H of the magnetic flux B in a magnetic circuit, and curve (2) represents the variation with progressively increasing positive magnetomotive force H of the magnetic flux B in a magnetic circuit when the magnetic member upon which said magnetomotive force is impressed is surrounded by a solenoid through 70 which high frequency electrical oscillations are passing. It will be noted that the ordinates of curve (2) are greater for a given magnetomotive force than the ordinates of that part of curve (1) comprised between 75 H = 0 and H = a, when H is increasing, on account of the increase of the permeability of the magnetic member which is effected by the passage of the high frequency oscillations around the solenoid inclosing said 80 member.

In the normal condition of the apparatus, the magnitude of the magnetic flux in the cores 2', which preferably are magnetically saturated, is represented by the ordinate 95 a b. When the oscillations to be detected pass through the solenoids 2, 2, the resulting increase in the permeability of the cores 2' or, in other words, the resulting decrease in the magnetic reluctance of said cores, results in a 100 greater magnetic flux in the magnetic circuit of which said cores form a part. This increase in magnetic flux is represented by the difference between the ordinates a b and a c, namely, b c, and results in a slight movement 105 of the preferably balanced diaphragm 3 toward the cores 2'. Said movement of the diaphragm results in a variation of the resistance of the contact formed by the carbon button 6 with the pin 4 and therefore pro- 110

duces a variation in the current flowing in the circuit of the telephone T, whereby the signal to be received is made manifest to the receiving operator.

5 When the oscillations cease to flow in the circuit of the solenoids 2, 2, the permeability of the cores 2' recedes to its normal value, indicated in Fig. 4 by the ordinate *a b*, so that it will be seen that my oscillation detector is 10 of the "self-restoring" type.

Although I have shown my oscillation detector associated with an elevated conductor by means of a resonant circuit inductively related to said elevated conductor, it is to be 15 understood that said detector may be associated with a receiving conductor in any manner which is suitable for the purpose.

Referring to the practical embodiment of my invention which I have illustrated in Fig. 2 for the purpose of more fully disclosing the same, 16 represents a base plate which may be of wood and which may rest upon a sheet of felt 17 or other vibration-absorbing material. The magnet 1 is shown as secured to the base 16 by the screws 14, 14', through the former of which electrical connection is made between the battery B and the permanent magnet 1 and thence by the pin 4 to the carbon button 6 and diaphragm-support 8, 30 which is secured to the base by the screw 15, electrically connected through the telephone T to said battery. The diaphragm 3 may be held by the springs 11, 11 in a recess cut into the support 8. A frame 9 may be bolted to 35 the support 8 and to said frame the balancing magnet 7 may be adjustably supported by the nuts 10. Better results are obtained if the oscillation detector is inclosed in a bell jar 20 secured in any suitable manner to the base 16 and evacuated by suitable apparatus connected with the outlet 18 and provided with a valve 19.

I claim:

1. An oscillation detector comprising a 45 magnetizable member forming part of a magnetic circuit, a source of constant unidirectional magnetomotive force associated with

said magnetic circuit, means whereby the permeability of said magnetic circuit may be 50 increased by the electrical oscillations to be detected, a movable member of magnetic material arranged so as to be actuated by the resulting increase in the magnetic flux in said magnetic circuit, an electric circuit including a signal-indicating device and a source of electromotive force, and means whereby current variations may be created in said electric circuit by the movement of said movable member. 60

2. An oscillation detector comprising a soft iron core, a coil surrounding said core and forming part of an oscillation circuit, a permanent magnet in fixed relation with respect to said core, a diaphragm actuated by the increase in the magnetic flux in said core resulting from the passage of the electrical oscillations to be detected through said coil, an electric circuit including a signal-indicating device and a source of electromotive force, and means whereby current variations may be created in said electric circuit by the movement of said diaphragm. 70

3. An oscillation detector comprising a soft iron core, a coil surrounding said core and forming part of an oscillation circuit, a permanent magnet in fixed relation with respect to said core, a balanced diaphragm actuated by the increase in the magnetic flux in said core resulting from the passage of the electrical oscillations to be detected through said coil, an electric circuit including a signal-indicating device and a source of electromotive force, and means whereby current variations may be created in said electric circuit by the movement of said diaphragm. 75 80 85

In testimony whereof, I have hereunto subscribed my name this 24th day of July 1906.

CHARLES E. RUSSELL.
